UNITED STATES PATENT OFFICE.

WILLIAM A. ZIMMERMAN, OF LOS ANGELES, CALIFORNIA, ASSIGNOR TO
NATIONAL CASH REGISTER COMPANY, OF JERSEY CITY, NEW JERSEY,
A CORPORATION OF NEW JERSEY.

CASH-REGISTER.

SPECIFICATION forming part of Letters Patent No. 739,530, dated September 22, 1903.

Application filed March 10, 1902. Serial No. 97,448. (No model.)

To all whom it may concern:

Be it known that I, WILLIAM A. ZIMMERMAN, a citizen of the United States, residing at Los Angeles, in the county of Los Angeles 5 and State of California, have invented certain new and useful Improvements in Cash-Registers, of which I declare the following to be a full, clear, and exact description.

My invention relates to improvements in 10 cash-registers, its object being to provide means whereby when the same amount is registered successively it is necessary to press the amount or value keys only at the time of the first registration.

15 In the drawings, Figure 1 is a sectional view through part of a cash-register, showing a bank of value-keys and my invention applied thereto. Fig. 2 is a view of the special repeat-key that I employ. The inclosing tube 20 is also shown in elevation in a separate view. Fig. 3 shows the special detent-plate, with the repeat-key in operative engagement therewith. Fig. 4 shows a top plan view of the repeat-key.

25 I thought it unnecessary to complicate the drawings by illustrating the indicating, registering, and other operative parts of the cash-register, as I believe the invention can be fully understood without reference to those 30 parts.

My invention may well be applied to a cash-register of the class, for example, shown in the patent to John H. McCormick, No. 610,492, dated September 6, 1898.

35 Referring now to the drawings, the numeral 6 designates the fixed side frame of the machine. The registering-segment 7, having the yoke 8, is pivoted upon the central shaft 9, but *per se* forms no part of my present invention. The value-keys 10 are arranged 40 preferably, though not necessarily, on the arc of a circle. Each key extends through and has a bearing in the key-frame 11, which is supported upon the transverse shafts 12, which 45 connect the side frames of the machine. Each key has a detent-pin 13 and a spring 14, which abuts at one end against the detent-pin and at the other against the inner ledge of the key-frame and operates to retain the keys in 50 normal outward position. Lying adjacentall

of the keys and pivoted on the central shaft 9 is the regular detent-plate 15, which has a series of hooks 16, one for each of the nine value-keys 10. The devices thus far described operate in the usual manner—that is to say, 55 when a key is pressed the detent-pin 13 on striking the inclined edge 17 of the hook 16 forces the detent-plate upward until the detent-pin passes under the inner point of the hook 16, whereupon the detent-plate drops 60 back to normal position, holding the key engaged. If now another key be depressed, the detent-plate will be raised in the same manner, releasing the previously-raised key and engaging and holding the key last pressed. 65 In the usual manner, also, if a key be pressed and the machine operated the detent-plate is struck by some operative part of the machine and raised, so as to automatically release the operated key. This is the mode of operation 70 of most, if not all, of the machines of this type now on the market.

The general operation by which the detent-plate is raised at each operation of the machine so as automatically to release any operated key is fully set forth in the aforementioned patent, No. 610,492, and comprises a rocking frame which is suitably journaled in the lower part of the main frame 6 and is adapted to coöperate with an arm *j*', extending downward from the detent-plate 15, and this rocking frame is operated by the movement of the drawer, so that on the outward movement of said drawer the rocking frame is not moved; but on the closing of the drawer 80 the rocking frame is rocked upward, so as to come in contact with the aforesaid arm *j*', and thereby lift the detent-plate and release the keys, all of which releasing movement is fully set forth and shown in the aforesaid patent. 85

It often happens, particularly at certain times and in certain places, that the clerk or other person operating the machine has to register the same amount successively. For example, in drug-stores at rush times the 95 clerk has often to register a number of five-cent sales successively and rapidly. As the machines have been heretofore made in order to register successive sales he must each time press the five-cent key, because, as stated, 100

the machine each time automatically releases the key last pressed. The object of my invention is to provide an arrangement whereby it shall be optional with the clerk or person operating the machine whether the key last pressed shall be automatically released. To this end I provide what I may call the "repeat-key." This consists of the finger-button 18, the outer tube 19, and the stem 20. The repeat-key may have any suitable location, but is preferably placed at the top of one of the series of amount or value keys, as is shown in Fig. 1. In like manner with the other keys this special or repeat key has a bearing in the supplemental frame 11. In like manner also it is provided with the detent-pin 21, which is secured in the tube 19 and extends laterally therefrom. The stem 20 at its lower end and below the lower end 20 of the tube 19 is likewise provided with a lateral locking-pin 22, which lies in a plane preferably at right angles to that of the detent-pin 21. Close beside the regular detent 15 and between it and the keys lies the special 25 detent 23. (Shown in Fig. 4.) This is also pivoted upon the central shaft 9 and is provided with nine hooks 24, having inclined faces 25, exactly like the hooks 16, with the inclined faces 17. The difference between 30 the regular detent-plate and the special detent-plate consists in the fact that the latter has an extension 26, comprising a shoulder 27, an inclined face 28, and a deep locking-notch 29. It is evident that the repeat-key 35 has two motions—that is to say, it may be pressed in in the direction of its length or the shank may be turned within the tube. If the repeat-key be pressed in, the special detent-plate is thereby raised, so that the inclined faces 25 of the hooks are entirely out 40 of the paths of the detent-pins 13 of the value-keys. When in this position, the special detent has no effect whatever on the operation of the machine. The special detent may be 45 moved to this position by fully depressing the repeat-key, whereupon the pin 21 of the repeat-key becomes seated in the deep locking-notch 29. If now the repeat-key be given a turn in the direction of the arrow, Fig. 4, 50 the locking-pin 22 will be moved under the shoulder 27, so as to lock the detent-plate in its upper position and the repeat-key in its operative position. As previously stated, when in this position the special detent-plate 55 has no effect whatever on the operation of the machine, and the regular operation of the machine will automatically unlock the last-operated value-keys and permit them to return to normal position. If the repeat-key, however, be in outward position, as 60 shown in Fig. 1, then the hooks 24 are exactly coincident with the hooks 16 of the regular detent-plate. Under this construction the last-operated value-key is not released by the 65 regular operation of the machine, but only

by the pressing in of some other value-key. Of course the regular detent-plate will still be operated in its regular manner; but the special detent-plate will not be moved by the operation of the machine, and hence will not 70 release the last-operated key from depressed position until the subsequent operation of another key, whereupon of course both the detent-plates will be raised, thereby releasing the last-operated key. If the same amount 75 were to be registered successively or if even the same value-key in any bank were to be used successively, with my improved device it would not be necessary to repress that key in registering the successive sale, because, 80 as stated, it will remain in operative or depressed position until released by the subsequent pressing of another value-key in the same series.

In machines of the class to which my invention is shown as applied after the keys are pressed there is usually a subsequent operation necessary to complete the registration—such, for example, as the turning of a crank or the operation of a special push-button—and it will readily be observed that when my invention is applied to such a machine to register successive sales of the same amount it is only necessary to turn the crank or press the special push-button.

Having thus described my invention, I claim as new and desire to secure by Letters Patent—

1. In a cash-register, the combination with a series of value-keys, and a regularly-releasable detent-plate arranged to engage any key and hold it in depressed position, of a specially-releasable detent-plate which is also arranged to engage the operated key, substantially as and for the purpose described.

2. In a cash-register, the combination with a series of value-keys, and a regularly-releasable detent-plate arranged to engage an operated key and hold it in its operative position, of a specially-releasable detent-plate which is also arranged to engage the operated key, with provisions for disengaging said detent-plate therefrom upon the subsequent operation of another key.

3. In a cash-register, the combination with a series of value-keys, of a detent-plate arranged to engage and hold the operated key, a special detent having a hooked projection for each value-key arranged to also engage the operated value-key and hold it in operative position, and a repeat-key cooperating with the special detent-plate and arranged to hold it in inoperative position.

In testimony whereof I affix my signature in the presence of two witnesses.

WILLIAM A. ZIMMERMAN.
